UNITED STATES PATENT OFFICE.

HENRY MONAHAN, OF MERIDEN, CONNECTICUT.

LINE HOLDER.

1,423,868.

Specification of Letters Patent. Patented July 25, 1922.

Application filed April 13, 1922. Serial No. 552,405.

To all whom it may concern:

Be it known that I, HENRY MONAHAN, a citizen of the United States, residing at Meriden, in the county of New Haven and State 5 of Connecticut, have invented a new and useful Improvement in Line Holders; and I do hereby declare the following, when taken in connection with the accompanying drawings and the characters of reference marked 10 thereon, to be a full, clear, and exact description of the same, and which said drawings constitute part of this application, and represent, in—

Fig. 1 a perspective view of two pins constructed in accordance with my invention and shown as connected by a line.

Fig. 2 a broken side view of one of the pins.

This invention relates to improvement in 20 line holders such as are commonly used by gardeners, walk-layers, and others, where it is desired to support a line for straight edges, the object of the invention being to provide holders or pins by which a line may 25 be held, and the invention consists in the construction hereinafter described and particularly recited in the claims.

In carrying out my invention, I employ a long, tapered pin 5, preferably formed with 30 a head 6 and formed in one side with a notch 7. Secured to the notched side of the pin, and below the notch, is a finger 8, which projects above the upper end of the notch, and which is bowed outward from the pin.

These pins are used in connection with a 35 cord or line 9, the ends of which are knotted at the desired points, and the ends of the line are inserted between the fingers and the pins, so as to enter the notches 7. These pins are driven in at the desired point, and the line 40 stretched between them in the usual way of using a line for forming a straight edge in gardening, walk-laying, etc., and provides a simple and convenient means for holding a line, and with which the line may be readily 45 engaged and removed, when desired.

I claim:

1. A line holder, comprising a pin formed in one side with a notch, and a finger secured to the notched side of the pin and projecting 50 upward beyond the upper end of the notch.

2. A line holder, comprising an upwardly-bowed pin formed in one side with a notch, and a finger secured to the notched side of the pin and extending above the upper end 55 of the notch.

3. A line holder, comprising a pin formed with a head and in one side with a notch, and a finger on the notched side of the pin, the said finger projecting upward, across the 60 face of the notch.

In testimony whereof, I have signed this specification in the presence of two subscribing witnesses.

HENRY MONAHAN.

Witnesses:

FREDERIC C. EARLE,
MALCOLM P. NICHOLS.
